UNITED STATES PATENT OFFICE.

JOHN B. BARNETT, OF FORT WORTH, TEXAS, ASSIGNOR, BY DIRECT AND MESNE ASSIGNMENTS, OF TWO-THIRDS TO H. C. HERMSMEYER, OF FORT WORTH, TEXAS, AND ONE-THIRD TO R. D. ERWIN, OF MCKINNEY, TEXAS.

DISPLAY ADVERTISING-MACHINE.

1,242,639.

Specification of Letters Patent.

Patented Oct. 9, 1917.

Application filed September 28, 1915. Serial No. 52,988.

To all whom it may concern:

Be it known that I, JOHN B. BARNETT, a citizen of the United States, residing at Fort Worth, in the county of Tarrant and State of Texas, have invented certain new and useful Improvements in Display Advertising-Machines, of which the following is a specification.

My invention relates to advertising devices and more particularly to display advertising devices; and the object is to provide a machine which will carry a plurality of large frames, for advertising sheets and which will hold the sheets stationary temporarily at regular intervals to expose the sheets with full face views at regular intervals, exposing one face of a sheet for a fixed length or period of time and then in quick succession showing the other face of the sheet. Another object is to provide a machine which may be driven by any suitable power, as by a small electric motor, and which will be operated without the continual attention of the operator. Other objects and advantages will be fully explained in the following description and the invention will be more particularly pointed out in the claims.

Reference is had to the accompanying drawings which form a part of this application.

Figure 1 is a side elevation of the machine, showing two frames for carrying advertising sheets, a part of the lower rim being broken away. Fig. 2 is a detail view, showing a hold back lug for retarding the frames. Fig. 3 is a plan view of the retarding stop which cooperates with the hold-back lug. Fig. 4 is a front elevation of the same. Fig. 5 is a rear view of the same. Fig. 6 is a plan view of a releasing cam for releasing the retarding lugs from the retarding stop. Fig. 7 is an edge view of a bracket which carries a lug to engage the cam shown in Fig. 6. Fig. 8 is a face view of the same. Fig. 9 is an enlarged plan view of the operating mechanism. Fig. 10 is a diagrammatic plan view in part, showing the manner of positioning the advertising sheets. Fig. 11 is a side elevation of a part of the operating mechanism, showing the manner of engagement of the carrying dog with the advertising frames. Fig. 12 is a side elevation of the operating chain and the dog carried

thereby. Fig. 13 is a plan view of a part 55 of the devices shown in Fig. 11 on a larger scale. Fig. 14 is a detail view of the preliminary retarding device for the advertising frames. Fig. 15 is a detail view of the driving gear for the sprocket chain. 60

Similar characters of reference are used to indicate the same parts throughout the several views.

This invention comprises a rotary machine carrying a number of vertically disposed 65 frames which are to be exposed to view at predetermined positions and for predetermined lengths of time. The machine is provided with a frame composed of upper and lower rim members 1 and 2 and uprights 3. 70 The frame may be closed if desirable and that portion of the upright portion of the frame extending from the point 4 to 4 on the front of the machine may be provided with transparent plates, as of glass, to expose display advertising matter positioned within the frame. A rotary shaft 5 is journaled in bearings 6 and 7, the bearing 6 being attached to the roof bars 8 and the bearing 7 being mounted on a foundation beam 75 9. Disks 10 and 11 are fixedly attached to the shaft 5 and a plurality of rectangular frames 12 are pivotally connected to the disks 10 and 11, the inner upright frame piece 13 of the frame 12 having extensions 80 above and below the frame 12 for engaging the disks 10 and 11. The advertising sheets are to be attached to the frames 12. The frames 12 are provided with radiating arms 85 or handles 14 by which the frames 12 are moved. The handles 14 are attached to the shaft 5 and rigidly braced to the bottom parts of the frames 12. The operating means will engage the handles 14 instead of the frames 12. 90 95

Means are provided for rotating the frames 12 by means of the handles 14. A motor 15 drives a pinion 16 which drives a cog wheel 17. The cog wheel 17 is rigid with a bevel pinion 18 which meshes with 100 and drives a bevel cog wheel 19 which is rigid with a sprocket wheel 20. A sprocket chain 21 is driven by the sprocket wheel 20 and runs on a series of idlers 22 which are arranged over a track 23 which is oval 105 in part and a part of which is concentric with the disks 10 and 11, this part being a regular curve and extending from point 24

to point 25. A dog 26 is pivotally connected to the chain 21 and is dragged along on the track 23 by the chain. This dog has an upstanding hook 27 and engages an arm 14 for moving a frame 12 from the point 24 to the point 25. At the point 25, the dog 26 drops down the incline 28 in the track 23 and releases the arm 14. In traveling from the point 24 to the point 25, a frame 12 rotates in its bearings in the disks 10 and 11.

Fig. 9 illustrates the two positions in which the frames 12 are held stationary for exhibition purposes. The front face of an advertising sheet will be seen on the left of Fig. 9 and the rear face of another sheet will be seen on the right of Fig. 9 at the same time and for the same length of time. The frames 12 are held at the point 24 by a spring-actuated dog 29 which is provided with an upstanding hook 30, the dog being held normally in the elevated position by a spring 31 and the dog being pivotally mounted in a bracket 32, which is attached to the beam 9. The hook 30 stands normally in the path of the arms 14. The dog 29 has an inclined ledge 33 and the dog 26 has lip 34 which rides up on the ledge 33 and bears the dog 29 down and thus releases an arm 14 which is immediately caught by the hook 27 of dog 26. The dog 26 then carries the arm 14 on around to the point 25. Means are provided for preventing displacement of the dog 26 while this dog is taking an arm 14 from the dog 29. An overhanging flange 35 is supported just above the path of the chain 21 by a bracket 36. The dog 26 has a lateral lip 37 which runs under the flange 35 while the arm 14 is being released from one dog and caught by the other. The dog 26 will not be displaced laterally because of the chain 21 and the ledge 33. The arm 14 is thus held stationary while the dog 26 makes the entire circuit about the track 23. The arm 14 on the opposite side at point 25 is also held stationary while the arm at 24 is held stationary. Each frame 12 carries an arm 38 which has a depending lug 39. A cuff or bracket 40 is attached to a rigid post 41 and has an upstanding stop lug 42. A spring buffer catch 43 is mounted on the bracket 40. This catch is composed of two parts hingedly connected together and held in the path of the lugs 39 by a spring 44. When the lug 39 strikes the buffer 43, the frame 12 will be stopped gradually, the lug 39 passing the buffer while the buffer stops the force of the frame 12 and the lug 39 is caught against the stop 42. The frame 12 will thus be held against movement in either direction, the lug 39 being caught between stop 42 and the end of buffer 43. The lug 39 is released from the stop 42 when the disk 11 begins to rotate. The disk 11

commences to rotate just after the dog 26 first engages an arm 14. The base of the machine includes two beams 44 and 45. A casting 7 is attached rigidly to the beam 44 and has an upstanding cam 47. Each frame piece 13 has an arm 48 rigid therewith and each arm has a depending lug 46. The lug 46 engages the cam 47 when the arm 14 commences to move. The lug 46 by bearing against the cam 47 which is stationary causes a rotation of the disk 11 and this action moves all the frames 12. This action also causes sufficient longitudinal or outward movement of the frame 12 which is standing at the point 25 to release the lug 39 from the stop 42. At the same time the disk 11 is being thus moved the dog 26 is swinging a frame 12 with its advertising sheet from showing the front face at 24 to the position at 25 to show the rear face. The disks 10 and 11 are thus moved at regular intervals and two frames stand in the positions at 24 and 25 for fixed periods of time, standing while the dog 26 makes the circuit from point 25 around to point 24. When the dog 26 arrives at the point 24, it engages another arm 14 and moves the frame 12 around to the point 25.

From the point 25 around past the motor 15, the frames 12 move in an irregular or desultory manner and means must be provided for preventing several of the frames 12 from accumulating at the dog 29. For this purpose a retarding device is provided. A standard 48 is attached to the base of the frame and carries an antifriction roller 49. The first arm 14 that reaches the roller will be stopped by this roller and if other frames 12 are crowded together they will stop against the bar 50. The roller 49 must be so positioned that the arm 12 will not leave the roller 49 until the disk 11 is moved in the manner above described. Each arm 14 will project farther past the roller 49 than the arm in front, as shown in Fig. 9. The moving of the disk 11 will cause a sufficient longitudinal movement of the arm 14 to permit it to pass the roller 49 and the arm will move along until it stops against the hook 30 of the dog 29. The dog 26 will then come along and release the arm from hook 30, as above described. Additional frames 12 will be stopped by the arms coming against the bar 50 which is placed at such angle that the ends of the arms 14 will come against the bar at different times and thus prevent the frames 12 from crowding against each other.

Means are provided for stopping the motor in case of accident to prevent damage and breaking of the machine. A switch 53 is provided for breaking the motor current. One arm 52 of the current wire is connected to a bar 54 and the other arm 51 is connected to the key 53. The switch key is standing

in contact, as shown by the drawings. The key can be automatically opened in case of accident. The idle roller 55 is mounted in a bar 56 which is pivotally mounted at 57. 5 The bar 56 is held in its normal working position by a rod 58 which is connected thereto and the spring 59. Straps 60 and 61 are pivotally connected to a bar 62. The strap 60 is pivotally connected to the bar 56 10 and the strap 61 is rigid with the track bar 23. A guide 63 for the bar 62 is attached to the bar 56. In case of abnormal strain on the sprocket chain 21, the spring 59 will permit a movement of the bar 56 which will 15 swing on its pivot 57 and thus push on the strap 60 which will actuate the bar 62 to open the switch 53 and thus stop the motor 15. A platform 64 may be used to brace the track 23.

20 In order to prevent backward turning of the disks 10 and 11, friction pawls 66 may be pivotally connected with the machine frame to bear on top of the disk 10.

What I claim is,—

25 1. A display advertising machine comprising a main frame, an upright shaft journaled therein and carrying a disk at the upper part and a disk on the lower part, a plurality of display frames pivotally mounted 30 in said disks and each frame having a portion of the pivot post projecting through the lower disk, an operating arm attached to the underside of each frame and a cam lever attached to the lower projecting portion of 35 each pivot post, means for driving or turning each frame periodically, and a cam engaged by said cam lever for simultaneously moving said disks.

2. A display advertising machine comprising a main frame, an upright shaft journaled in said frame and carrying upper and lower disks, a plurality of display frames journaled in said disks and the pivot post of each frame projecting through the lower 45 disk, a cam lever rigid with each pivot post and an operating arm rigid with the lower part of each frame, an upwardly projecting cam in the path of said cam levers, means for periodically moving said display frames 50 and said disks being simultaneously moved by said cam and said levers, and means for locking a pair of frames in displaying positions after each moving of a frame.

3. A display advertising machine comprising a main frame, an upright shaft journaled in said frame, an upper and a lower disk mounted on said shaft, a plurality of pivot posts journaled in said disks and projecting through the lower disk and display 55 frames carried by said pivot posts, operating arms rigid with the lower sides of said frames, cam levers rigid with the projecting ends of said pivot posts, a cam in the path of said cam levers, means for turning said 60 operating arms periodically, said cam levers 65

and cam serving simultaneously to move said disks, and means for locking each display frame for a short interval of time prior to its moving and means for locking each display frame for a short interval again 70 after its moving.

4. A display advertising machine comprising a main frame, an upright shaft journaled in said frame, an upper disk and a lower disk mounted on said shaft, a plurality of vertically disposed display frames journaled in said disks, a driving mechanism for turning each frame one half turn periodically, means operatively connected with said display frames and with the base 75 of said machine frame for moving said disks one step simultaneously with the turning of each display frame, means for locking each display frame stationary after each turning thereof, means for releasing said display frame at the next moving of said disks, a locking mechanism for locking each display frame stationary prior to its turning, and means carried by said driving mechanism for automatically releasing said display frame from said locking mechanism 80 and for engaging the frame for turning the same.

5. A display advertising machine comprising a main frame, an upright shaft 95 journaled in said frame, an upper disk and a lower disk mounted on said shaft, a plurality of vertically disposed display frames journaled in said disks, a driving mechanism for turning each display frame one 100 half turn including a sprocket chain, an oval track, a part thereof being a semi-circle, a sprocket wheel for driving said chain and idlers about said track for supporting said chain, a locking mechanism for locking each 105 display frame stationary prior to its turning and means for locking each display frame stationary at the end of its half turning, said track having an inclined drop at the latter position, and a dog carried by said chain and trailing on said track for automatically releasing each display frame from 110 said locking mechanism and for engaging the frame to turn it, and said dog automatically releasing said frame by dropping down 115 said inclined drop.

6. A display advertising machine comprising a main frame, an upright shaft journaled in said frame, an upper disk and a lower disk mounted on said shaft, a plurality of vertically disposed display frames journaled in said disks, a driving mechanism for turning each display frame periodically including a sprocket chain, an oval track, a part of which is semicircular, a sprocket wheel for driving said chain and idlers mounted about said track for supporting said chain, a locking mechanism for locking each display frame stationary at the commencement of the semicircular portion 120 125 130

of said track and means for locking each display frame stationary at the end of the semicircular portion of said track, said track having an inclined drop at the latter position, a dog carried by said chain and trailing on said track for automatically releasing each display frame from said locking mechanism and engaging the frame for turning the same and automatically releasing the frame by dropping down said inclined drop after having turned the frame a half turn, and means operatively connected with each display frame and with the frame of the machine for automatically moving said disks a step at a time simultaneously with the turning of each frame and releasing each display frame from said locking means at the end of the semicircular portion of said track.

20 7. A display advertising machine comprising a main frame, an upright shaft journaled in said frame, an upper and a lower

disk mounted on said shaft, a plurality of vertically disposed display frames journaled in said disks, means for turning each frame periodically and successively one half turn, means operatively connected with each display frame and with the main frame for moving all of said frames and said disks one step simultaneously with the turning of each display frame, locking mechanism for locking each display frame stationary for a short period prior to the turning thereof, means for retarding the movement of said display frames to prevent crowding against said locking mechanism, and means carried by said turning means for automatically releasing each display frame from said locking mechanism and for engaging the frame for turning the same.

In testimony whereof, I set my hand this 28th day of June, 1915.

JOHN B. BARNETT.
